ATTORNEY

UNITED STATES PATENT OFFICE.

JAMES W. HENRY, OF GOODING, IDAHO.

HYDROCARBON-ENGINE.

1,267,547.

Specification of Letters Patent. Patented May 28, 1918.

Application filed October 30, 1917. Serial No. 129,328.

To all whom it may concern:

Be it known that I, JAMES W. HENRY, a citizen of the United States, residing at Gooding, in the county of Gooding and State of Idaho, have invented certain new and useful Improvements in Hydrocarbon-Engines, of which the following is a specification.

This invention relates to improvements in hydro-carbon engines and more particularly to a multiple stroke engine adapted to complete the four strokes of each piston upon each single revolution of the power shaft.

One of the principal objects of the invention is to provide a cam shaft in place of the ordinary crank shaft; the cam shaft being disposed to be rotated by the pistons in a manner that will cause the cam shaft to revolve once upon two complete reciprocations of the pistons.

A further object of the invention is to provide a four cycle hydro-carbon engine having a plurality of driving pistons operating in cylinders adapted to receive an explosive charge at predetermined intervals governed by a direct connection of the valves with the cam shaft thus eliminating the use of timing gears now generally employed on engines of this character.

The invention further aims to provide an engine of this character that will be constructed to cause strokes of the piston to be multiplied two fold with respect to the revolutions of the power shaft, whereby a greater speed of the pistons may be maintained thereby permitting the use of a comparatively small quantity of explosive mixture ejected into the cylinder upon each power stroke of the piston.

A further object of the invention is to provide an engine of this character that will be more efficient in operation and less complicated and lighter in construction than the engines now generally used.

A further object of this invention is the provision of a device of this character which is simple in construction but durable and well adapted to withstand the rough usage to which devices of this character are ordinarily subjected.

For a full description of the invention and the advantages and merits thereof, reference is to be had to the following description and the accompanying drawings, where-

in is illustrated the preferred form of my invention in which:

Figure 1 is a top plan.

Fig. 2 is a vertical section taken on the line 2—2 of Fig. 1. 60

Fig. 3 is a section taken on the line 3—3 of Fig. 2.

Referring to the drawings wherein is illustrated the preferred form of my invention, in which like numerals of reference 65 indicate corresponding parts throughout the several views, the engine casing 1 has the driving shaft 2 extended therethrough and this shaft may be of any desired length according to the number of cylinders employed in constructing the engine. Mounted upon the top of the casing are the laterally spaced apart cylinders 3 and 4 which are disposed vertically and have their interiors in communication with the interior of the 75 casing 1. These cylinders are spaced at equal distances from the center line of the casing and are each provided with a piston 5 connected to a connecting rod 6 extending downwardly into the casing 1. 80

Pivots mounted within the casing, on the ears or lugs 7 carried by the top wall of the casing, is a rocker beam 8 which, in the present instance, is constructed of frame bars 9 connected at their proximate ends 85 and pivoted, on the pin 10, to the lugs 7. The outer ends of the frame bars 9 are bifurcated and the terminals of the bifurcated ends are integrally connected to the brace bars 11 which are laterally spaced 90 apart and maintain the arms 9 in proper position and prevent collapsing of the beam when the same is in operation. The ends of the bifurcated portions of the arms 9 are apertured to receive pivot pins or journals 95 12 each of which carries a roller or wheel 13. The lower ends of the piston rod are also bifurcated as shown in Fig. 3 of the drawing and these bifurcated ends extend around the rollers and are pivotably connected to the journals 12. 100

Mounted upon the shaft 2 is a cam 14 which, as shown to advantage in Fig. 2 of the drawing, is an elongated plate having each end rounded and its longitudinal marginal edges straight thus forming a cam surface against which the peripheries of the rollers 13 are engaged. 105

The rocker beam is so mounted as to cause the rollers 13 to contact with the cam surface 110

at all times as shown by full and dotted lines in Fig. 2.

Mounted upon the shaft 2 is a valve cam 15 engaged by the rollers 16 carried by the ends of the valve rods 17 which extend to the top of the cylinders and are connected to rocker arms 18 pivotally mounted and which are joined to the valve stems 19 of the valves 20. These valves are adapted to open and close the ports in the top of the cylinders for permitting the intake of an explosive charge and the exhaust of the gases after the explosion occurs.

In operation, the explosive charge will be supplied to the cylinders in any preferred manner and assuming the structure to be in the position shown in full lines in Fig. 2, the explosion occurring in the cylinder 4 will force the piston downwardly and the downward pressure will be exerted by the roller 13 on the surface of the cam and cause the same to rotate in the direction indicated by the arrow in Fig. 2. The frame or rocking beam being pivoted will cause the roller to swing inwardly toward the center of the shaft and thus impart rotary movement to the cam which, being fixed to the shaft, will cause the shaft to rotate. This downward movement of the piston in the cylinder 4 will cause an upward movement of the piston in the cylinder 3, this being the exhaust stroke of the piston. By virtue of the continual contact of the rollers 13 with the cam, however, each piston will have made a complete reciprocation within its cylinder when the cam has moved around to the vertical position shown by dotted lines in Fig. 2, the shaft 2 having made only a half a revolution. Therefore, the piston in the cylinder 4 has received its power and exhaust stroke and the piston in the cylinder 3 has received its exhaust and intake stroke.

The cylinder 3 will then receive its power and compression stroke and the cylinder 4 its intake and compression stroke. In this manner the four strokes are completed in each cylinder upon a single revolution of the cam. And two cylinders will thereby accomplish the work of four cylinders of the ordinary type employing a crank shaft. The rollers 16 are always in contact with the cam 15 and since the valves 20 are opened for the purpose of admitting the explosive charges by direct contact with cam on the shaft 2 it will be seen that timing gears and counter shafts are eliminated and the pistons will operate at a comparatively great speed with respect to the speed of the shaft. A fly wheel may be mounted upon the shaft 2 in the usual manner for the purpose of properly balancing the shaft during the operation of the motor.

It will be also noted that the construction provides novel means for converting the reciprocatory movement of the piston into a

rotary movement which is transmitted to the shaft 2. Furthermore, the free ends of the piston rod 6 which carries the rollers 13 are given an oscillatory movement in addition to their reciprocation whereby the rollers will properly engage the cam surface to impart a rotary motion to the cam which transmits the same to the shaft 2. The oscillatory motion is obtained by virtue of the pivotal mounting of the rocker element 75 which has its ends connected with the rollers and the ends of the piston rods.

From the foregoing it will be observed that a very simple and durable hydro-carbon engine has been provided the detail of which embody the preferred form. I desire it to be understood, however, that slight changes in the minor details of construction may be made without departing from the spirit of the invention or the scope of the claims hereunto appended.

Claims:

1. An internal combustion motor comprising a plurality of cylinders, pistons and piston rods operable in the said cylinders, a straight drive shaft, rollers mounted upon the ends of the said piston rods, a rocker beam pivotally mounted and connected to the ends of the said piston rods and maintaining the said rollers in equally spaced relation during reciprocation of the said pistons, and a cam engageable with the said rollers and mounted upon the said shaft and adapted to receive the force exerted by the pistons on the said rollers for imparting one complete revolution to the said cam for every two complete reciprocations of each piston.

2. An internal combustion motor comprising a plurality of cylinders, pistons and piston rods, operable in the said cylinders, a straight drive shaft, each of the said pistons having a roller mounted on its free end, a rocker beam pivotally mounted and connected to the said rollers to maintain them in equally spaced relation, a cam including an elongated plate having rounded ends to provide a continuous cam surface engageable with the said rollers.

3. An internal combustion motor comprising a plurality of cylinders, pistons and piston rod, operable in the said cylinders, a straight drive shaft, each of the said pistons having a roller mounted on its free end, a rocker beam pivotally mounted and connected to the said rollers to maintain them in equally spaced relation, a cam including an elongated plate having rounded ends to provide a continuous cam surface engageable with the said rollers, and means mounted upon the shaft to govern the intake and exhaust of the said cylinders.

4. An internal combustion motor comprising a casing having a pair of cylinders mounted thereon, equally spaced from the

center line of the casing, a rocker beam pivotally connected to the casing at a point centrally located between the said cylinders, a roller mounted at each end of the said 5 rocker beam, pistons and piston rods arranged in the said cylinders, the free end of the said piston rods being connected to the ends of the said beam, a shaft mounted in the casing, and a cam mounted upon the 10 said shaft and including an elongated plate having the said shaft extended through its center, the said rollers being engageable with the marginal edge of the said plate.

5. An internal combustion motor comprising a casing having a pair of cylinders mounted thereon, spaced apart and at equal 15 distances from the center of the said casing, a rocker beam pivotally mounted within the casing at a fixed point between the said

cylinders, rollers carried by the ends of the 20 said rocker beam, pistons mounted for reciprocation in the said cylinders, piston rods connecting the said pistons with the ends of the said rocker beams whereby the said beam may be rocked on its pivot when the 25 said pistons are reciprocated, a shaft arranged within the casing, and a cam member including an elongated plate, centrally mounted on the said shaft and having straight longitudinal edges and rounded 30 ends engageable with the said rollers.

In testimony whereof I affix my signature in presence of two witnesses.

JAMES W. HENRY.
